[57] CLAIM

The ornamental design for front panel for a combined radio receiver and compact disc player, as shown and described.

DESCRIPTION

FIG. 1 is a view in perspective of a front panel for a combined radio receiver and compact disc player showing our new design;

FIG. 2 is a top plan view thereof;

FIG. 3 is a front elevational view thereof;

FIG. 4 is a left side elevational view thereof;

FIG. 5 is a right side elevation view thereof; and,

FIG. 6 is a bottom plan view thereof.

The housing shown in broken lines in the figures is shown for illustrative purposes only and forms no part of the claimed design.

FIG.4

FIG.5
